UNITED STATES PATENT OFFICE.

ROY F. GOULD, OF CHICAGO, ILLINOIS, ASSIGNOR TO RESERVE HOLDING COMPANY, OF KANSAS CITY, MISSOURI, A CORPORATION OF DELAWARE.

CORD CIRCUIT.

Application filed March 23, 1927. Serial No. 177,548.

- The present invention relates in general to cord circuits for telephone systems, but is particularly concerned with the provision of a cord circuit which is suitable for use in handling incoming calls from an automatic exchange when connections are desired with subscribers of a common battery exchange of the type in which a source of current is permanently connected to the subscribers' lines.
- 10 One object of the invention is to provide a cord circuit wherein the operator has her headset automatically connected in bridge of the incoming trunk when the answering plug is inserted in the answering jack, and where-
- 15 in her headset is automatically disconnected and ringing automatically takes place the instant the calling plug is inserted in the jack of the desired line.
- Another object is to provide a peculiar 20 ringing arrangement necessary due to the peculiar type of manual equipment used, and in the provision of a novel circuit arrangement for cutting off the ringing current as a result of the response of the called subscriber.
- 25 A further feature has to do with an arrangement in the cord for causing a reversing relay in the repeater of the incoming trunk to be actuated for the purpose of operating a subscriber's meter or for supervision.
- 30 Other features of the invention not specifically mentioned will become apparent from the detailed description and claims which follow.

In order to assist in describing the invention the same has been illustrated in a set of drawings comprising Figs. 1 and 2, which, when placed together with their corresponding lines in alignment, show sufficient of a telephone system to enable the invention to be explained and understood.

The substation circuit shown in Fig. 1 is of the usual type used in automatic telephone systems, while the one shown in Fig. 2 is of the type commonly used in common battery manual systems.

The circuits of automatic switches available to the substation A have not been shown, as switches of this character are well known and have no particular bearing on the invention.

Two automatic switches C and D, respectively, have been represented by the dotted rectangles which indicate a line switch in which the calling line terminates and which,

in turn, has access to a selector group as is customary.

The repeater E is of the general type ordinarily used in trunks extending between automatic and manual exchanges and is provided primarily to avoid the necessity of extending three conductors between the two exchanges. This circuit has been slightly modified and will be described in detail later.

In Fig. 2 is shown the answering jack of the trunk extending to the repeater E which is typical of answering equipment ordinarily used for this purpose.

The cord circuit O is for use in answering calls originating in the automatic exchange and for completing calls to the subscribers of the manual exchange. This cord circuit as previously stated, has quite a number of features of novelty all of which will be described hereinafter.

The answering jack J' and its associated relay group is of the type used in a common battery manual telephone system, developed by the Erickson Company of Sweden and installed in the Union of South Africa.

The various circuits and apparatus used having been generally described the invention will now be explained by giving a detailed account of the circuit operations which takes place consequent to the establishment of a connection from the substation A of the automatic exchange to the substation B of the manual exchange.

The subscriber at substation A upon desiring to extend a connection to the substation B of the manual exchange removes his receiver, responsive to which the lineswitch C, in the well known manner, extends the line to a first selector, indicated at D. The calling subscriber thereupon operates his calling device to position the switch D opposite a level of bank contacts in which terminate trunk multiples connected with the manual exchange. In the present instance we will assume that connection is extended to the repeater E.

Responsive to the seizure of this repeater the line relay 17 energizes and at its armature 14 connects the trunk conductor 26 to the winding of relay 24 and ground, and at its armature 10 causes the energization of holding relay 18. The relay 18 upon operating, at its armature 19 disconnects the trunk conductor 25 from the winding of relay 23 and battery and connects conductor 25 to winding

of relay 15 and battery; at armature 20 applies ground to the conductor 13 to prevent the release of the lineswitch C and the selector D, and at its armature 21 prepares an operating circuit for the slow release relay 22.

As soon as the winding of relay 24 is connected to conductor 26, it energizes in series with the relay 70 connected to the ring terminal of the jack J. The relay 24 operates and completes a circuit for slow release relay 23 which in turn operates for a purpose which will later be made clear. The relay 70 upon operating, causes the lamp L to light and to inform the operator of the incoming call.

15 The operator responds by inserting the plug P of the cord into the jack J thereby opening the circuit of relay 70 and extinguishing the calling lamp L. The insertion of the plug P into the jack J also causes the 20 battery supply for relay 24 in the repeater to be transferred to the relay 30 via the lower left-hand winding of the repeating coil R, and ring conductor 28. The relay 30 operates, at its armature 41 disconnects the release supervisory lamp L³ of the cord from the grounded sleeve conductor 29, and at its armature 42 and its working contact closes a point in the outgoing branch of the cord. As soon as the 25 plug P is inserted in the jack J a circuit is also completed for the operator's headset cut-on relay 40, from battery, winding of relay 40, armature 58 and its resting contact, armature 34 and its resting contact, to the sleeve of the plug and jack to ground. The relay 40, 30 therefore, operates and at its armatures 43 and 44 connects the operator's headset across the right-hand windings of the repeating coil R so that the operator may inquire and obtain 35 from the calling party the number of the desired party.

Since it has been assumed that the subscriber at substation B is desired the operator will proceed to test the line to determine whether the same is busy or idle. This is 40 done in the usual manner by the operator touching the tip of her plug to the sleeve of the jack. We will assume that the desired station is idle and therefore that the operator proceeds by inserting the plug P' into the 45 jack J'. Responsive to this operation the relays 47 and 67 operate. Relay 47 at its armatures 51 and 52 and their working contacts connects interrupted battery and interrupted ground, respectively, out over the tip and ring 50 sides of the cord; in this manner although the windings 68 and 69 used for feeding current to the substation B are permanently connected to the line conductors, they do not interfere with the transmission of ringing current. 55 Interrupted battery, or interrupted generator, as indicated on the drawing, Fig. 2, is meant to designate ringing current superimposed on battery current and applied intermittently, in conformance to the usual practice.

During the ringing operation a small amount of the ringing current leaks back to the calling line through the condenser 53 to inform the calling subscriber that the called line is being signalled. The relay 47 at its armature 48 and its grounded working contact completes a circuit for the supervisory lamp L²; at its armature 49 connects high resistance 46 and ground with the tip conductor of the incoming end of the cord, and at armature 50 completes a circuit for the slow-release relay 55. The resistance 46 is very high compared to the resistance of relay 15 in the repeater and this relay is therefore not operated at this time. Relay 55 at its armature 58 60 opens a point in the circuit of relay 40 causing this relay to restore and to disconnect the operator's head set, and at its armature 57 prepares a point in the operating circuit of relay 35.

Should the calling subscriber replace his receiver without having obtained the response of the called subscriber, line relay 17 will restore and at its armature 14 break the circuit of supervisory relay 30. This latter relay, upon restoring, at its armature 41 closes a circuit for lamp L³ to give the operator disconnect supervision and at its armature 42 disconnects the interrupted generator so that signalling of the called line is immediately discontinued.

We will assume that the called subscriber responds. While ringing current is actually being transmitted out over the line the winding of relay 68 is shunted. Accordingly, the removal of the receiver at the called station will be without effect until a silent period occurs. As soon, however, as the ringing current is interrupted momentarily, provided the called party at substation B has removed the receiver, line relay 68 energizes and connects battery by way of its working contact and armature, armature and working contact of relay 67 direct to this latter relay, thereby short circuiting relay 47, causing it to restore, to cut-off the ringing current. This relay also at its armature 48 opens the circuit of the lamp L² to notify the operator that the called subscriber has responded; at its armature 50 breaks the circuit of slow release relay 55 and at the resting contact of this armature momentarily completes a circuit, via working contact and armature 57, for the relay 35. This latter relay upon operating, at its armatures 36 and 39 opens points in the interrupted ground and interrupted generator ringing circuit so that the subsequent energization of the ringing relay 47 will be ineffective to again transmit ringing current to the called line, and at the working contacts of armatures 36 and 39 connects the tip and ring conductors 60 and 61 to the right hand windings of the repeating coil. This relay also at its armature 39 and its working contact connects relay 32 to the outgoing ring conductor 61 of 130

the cord which has battery supplied to it through the winding 69. Relay 32, therefore, operates and at its armature 33 locks up relay 35 independent of relay 55. The relay 35 also, at its armature 38 opens the circuit used during the ringing operation to inform the calling subscriber that the called subscriber was being signalled, and at its armature 37 closes an operating circuit for relay 15 of the repeater E, via the grounded retardation coil 45, working contact and armature 37, resting contact and armature 49, tip conductor 27 of the cord, trunk conductor 25, armature 19 and its working contact. The relay 15, upon operating causes the operation of the reversing relay 16 which, in a well understood manner reverses the direction of current flow back over the calling line to operate metering, pay station or supervisory equipment, depending upon the point from which the call originated.

In the description just given it will be recalled that the operator had her headset automatically connected to the incoming trunk when the call was answered and that when she extended the connection this equipment was automatically cut off. It is desirable in certain instances for the operator to come in on the connection to further supervise the call and in order to facilitate doing this an emergency key K is provided. This key may be operated at any time by the operator to cause the energization of relay 40 to connect her equipment with the cord. It will be understood however, that this key is ordinarily used only in an emergency.

The connection having been established it will now be assumed that the conversation has been completed and the calling subscriber is the first to restore his receiver. Responsive to this act line relay 17 deenergizes, at its armature 14 opens conductor 26 of the trunk, which causes the deenergization of relay 24 in the repeater E and of the supervisory relay 30 in the cord O, and at armature 10 breaks the circuit of relay 18 and momentarily closes a circuit for relay 22. The relay 18, upon deenergizing, removes ground from the holding conductor 13 to permit the switches D and C to be released from the connection so that they may restore to normal, and at its armature 19 switches the conductor 25 from the winding of relay 15 to the winding of slow release relay 23. Consequently the relay 15 and the reversing relay 16 controlled by it restore to normal, while the relay 23 is held energized independent of relay 24 and, following the deenergization of relay 22, its circuit having been broken at armature 21, applies ground to conductor 13, so long as the operator's cord circuit O remains connected with the answering and calling jacks, to make the trunk busy to selectors such as D.

In the cord O the deenergization of the re-

lay 30 at armature 41 causes disconnect lamp L³ to light up, and at armature 42 breaks the circuit of relay 32 which in turn breaks the holding circuit of relay 35. Relay 32 upon restoring at its armature 34 also completes a circuit for the relay 40 from the grounded sleeve of the jack J, sleeve conductor of the cord, resting contact and armature 34, resting contact and armature 58, and the winding of relay 40 to battery. This relay therefore responds to again connect the operator's set across the cord so that she may ascertain the reason for the subscriber at substation B not having restored his receiver.

If the receiver is replaced at the substation B before the subscriber replaces his receiver at substation A relay 68 will restore removing the short circuit from relay 47. This relay will accordingly be energized and at its armature 48 light the supervisory lamp L² to inform the operator that the called subscriber has replaced his receiver.

If the subscriber of the automatic exchange has not replaced his receiver, this will of course be obvious to the operator due to the unlighted condition of lamp L³. The operator will thereupon operate the key K and converse with the subscriber, and, in certain instances, connect the calling subscriber with another subscriber of the manual exchange.

What is claimed is:

1. In a telephone system, called lines, a source of current permanently connected in bridge thereof, a cord circuit for answering incoming calls and for extending connections to said lines, a source of intermittent ringing current for signalling said lines, a relay responsive to the connection of the cord with a line to cause said ringing current source to be applied thereover without disconnecting said current source in bridge of the called line, and a relay placed under control of the called subscriber, each time an interruption occurs in the application of ringing current to the called line for disconnecting said ringing current.

2. In a telephone system, a called line comprising two line conductors terminating in a jack, a current source and a first relay permanently connected in bridge of said conductors, a cord circuit for effecting connections to said line, a source of intermittent ringing current, a second relay responsive to the connection of said cord with said line for applying said ringing current thereover without disconnecting said first relay and said current source from across said line conductors, means at said called line for actuating said first relay, and means operated by said first relay for disconnecting said ringing current.

3. In a telephone system, a called line comprising two line conductors terminating in a jack, a current source and a first relay permanently connected in bridge of said con-

ductors, a cord circuit for effecting connections to said line, a source of intermittent ringing current, a second relay responsive to the connection of said cord with said line for applying said ringing current thereover without disconnecting said first relay and said current source from across said line conductors, means at said called line for actuating said first relay, and means operable by said first relay and effective only during an interruption in the application of said ringing current for disconnecting said ringing current.

4. In a telephone system, a called line comprising two line conductors terminating in a jack, a current source and a first relay permanently connected in bridge of said conductors, a cord circuit for effecting connections to said line, a source of intermittent ringing current, a second relay responsive to the connection of said cord with said line for applying said ringing current thereover without disconnecting said first relay and said current source from across said line conductors, means at said called line for actuating said first relay, and means operable by said first relay and effective only during an interruption in the application of said ringing current for short circuiting said second relay to discontinue the application of ringing current.

5. In a telephone system, calling and called lines, each comprising two line conductors terminating in a jack at an operator's position, a current source and a first relay permanently connected in bridge of the line conductors of said called line, a cord circuit for establishing connections between said lines, a source of intermittent ringing current, a second relay in said cord for automatically connecting the operator's telephone to said calling line upon connecting the cord therewith, a third relay in said cord for automatically disconnecting said operator's telephone and for automatically connecting said source of ringing current to said called line upon connecting said cord therewith, without disconnecting said first relay and said source of current from across said called line, means at said called line for actuating said first relay, and means operated by said first relay for disconnecting said ringing current.

6. In a telephone system, calling and called lines, each comprising two line conductors terminating in a jack at an operator's position, a source of current and a first relay permanently connected in bridge of the line conductors of said called line, a cord circuit for establishing connections between said lines, a source of intermittent ringing current, a second relay in said cord for automatically connecting the operator's telephone to said calling line upon connecting the cord therewith, a third relay in said cord for automatically disconnecting said operator's telephone and

for automatically connecting said source of ringing current to said called line upon connecting said cord therewith, without disconnecting said first relay and said source of current from said called line, means at said called line for actuating said first relay, and means operable by said first relay and effective only during an interruption in the application of said ringing current for disconnecting said ringing current.

7. In a telephone system, calling and called lines, each comprising two line conductors terminating in a jack at an operator's position, a source of current and a first relay permanently connected in bridge of the line conductors of said called line, a cord circuit for establishing connections between said lines, a source of intermittent ringing current, a second relay in said cord for automatically connecting the operator's telephone to said calling line upon connecting the cord therewith, a third relay in said cord for automatically disconnecting said operator's telephone and for automatically connecting said source of ringing current to said called line upon connecting said cord therewith, without disconnecting said first relay and said source of current from said called line, means at said called line for actuating said first relay, and means operable by said first relay and effective only during an interruption in the application of said ringing current for short circuiting said second relay to discontinue the application of said ringing current.

8. In a telephone system, calling and called lines, each comprising two line conductors terminating in a jack at an operator's position, a source of current and a first relay permanently connected in bridge of the line conductors of said called line, a cord circuit for establishing connections between said lines, a source of intermittent ringing current, a second relay in said cord for automatically connecting the operator's telephone to said calling line upon connecting the cord therewith, a third relay in said cord for automatically disconnecting said operator's telephone and for automatically connecting said source of ringing current to said called line upon connecting said cord therewith, without disconnecting said first relay and said source of current from said called line, means at said called line for actuating said first relay, and means operated by said first relay for disconnecting said ringing current.

9. In a telephone system, a calling line, a

- two conductor trunk line accessible thereto and terminating in a jack at an operator's position, a called line having two line conductors terminating in a second jack at said 5 position, a source of current permanently connected to said called line, a cord circuit for establishing connections between said trunk line and said called line, means in said cord circuit for automatically connecting the 10 operator's telephone to said trunk line responsive to connecting the cord therewith, a source of intermittent ringing current, means in said cord circuit for automatically connecting said ringing current to said called 15 line and for disconnecting said operator's telephone responsive to connecting said cord with said called line, without disconnecting said permanently connected current source from said called line, means controlled by said called line and including said permanently connected current source for disconnecting said ringing current, means for maintaining a 20 current flow over said trunk line prior to the disconnection of said ringing current, means for then altering the current flow over one conductor of said trunk line, and means responsive thereto for altering the current flow over said calling line for supervisory purposes.
11. In a telephone system, a calling line, a two conductor trunk line accessible thereto and terminating in a jack at an operator's position, a called line having two line conductors terminating in a second jack at said position, a source of current permanently connected to said called line, a cord circuit for 25 establishing connections between said trunk line and said called line, means in said cord circuit for maintaining a current flow over both conductors of said trunk line after establishing connection therewith, but prior to the completion of a talking connection with said called line, means in said cord circuit responsive after completion of said talking connection for altering the current flow over one conductor of said trunk line, and means responsive thereto for altering the current flow over said calling line.
10. In a telephone system, a calling line, a two conductor trunk line accessible thereto and terminating in a jack at an operator's position, a called line having two line conductors terminating in a second jack at said position, a source of current permanently connected to said called line, a cord circuit for 30 establishing connections between said trunk line and said called line, means in said cord circuit for automatically connecting the operator's telephone to said trunk line responsive

to connecting the cord therewith, a source of intermittent ringing current, means in said 40 cord circuit for automatically connecting said ringing current to said called line and for disconnecting said operator's telephone responsive to connecting said cord with said called line, without disconnecting said permanently connected current source from said called line, means controlled by said called line and including said permanently connected current source for disconnecting said ringing current, means for maintaining a 45 current flow over said trunk line prior to the disconnection of said ringing current, means for then altering the current flow over one conductor of said trunk line, and means responsive thereto for altering the current flow 50 over said calling line for supervisory purposes.

11. In a telephone system, a calling line, a two conductor trunk line accessible thereto and terminating at an operator's position, a called line, a cord circuit for establishing connections between said lines, means in said cord circuit for maintaining a current flow over both conductors of said trunk line after establishing connection therewith, but prior 60 to the completion of a talking connection with said called line, means in said cord circuit responsive after completion of said talking connection for altering the current flow over one conductor of said trunk line, and means responsive thereto for altering the current flow 65 over said calling line.

In witness whereof, I hereunto subscribe my name this 21st day of March, A. D. 1927.

ROY F. GOULD.
